Specification for Design.

Patented Apr. 4, 1922.

Application filed September 23, 1921. Serial No. 502,835. Term of patent 14 years.

To all whom it may concern:

Be it known that I, ARTHUR H. CLARK, a citizen of the United States, and resident of Plainfield, in the county of Union and State of New Jersey, have invented a new, original, and ornamental Design for Tire Treads, of which the following is a specification, reference being had to the accompanying drawing, forming a part hereof.

In the drawing, Fig. 1 is a plan view of the tire;

Fig. 2 a cross-sectional view on the line 2—2 of Fig. 1; and

Fig. 3 a similar view on the line 3—3 of Fig. 1.

I claim:

The ornamental design for a tire tread, as shown.

ARTHUR H. CLARK.
